UNITED STATES PATENT OFFICE.

HENRY VOGT AND ROBERT H. BURNS, OF BROOKLYN, NEW YORK.

FEED-WATER HEATER.

SPECIFICATION forming part of Letters Patent No. 394,526, dated December 11, 1888.

Application filed July 23, 1888. Serial No. 280,786. (No model.)

To all whom it may concern:

Be it known that we, HENRY VOGT and ROBERT H. BURNS, citizens of the United States, residing in Brooklyn, Kings county, 5 and State of New York, have invented certain new and useful Improvements in Feed-Water Heaters, of which the following is a specification, reference being had to the accompanying drawings.

Our invention relates specially to improvements in feed-water heaters, and has for its object the cleansing of the feed-water while passing through the heater, as well as the cleansing of the exhaust-steam of the grease 10 carried with it from the engine.

The improvements consist in the construction, arrangement, and combination of the several parts or portions comprising the heater, as hereinafter described and specified.

In the drawings, Figure 1 represents a vertical section through a heater embodying my improvements. Fig. 2 represents a plan view of the grease-extracting portion of such heater. Fig. 3 represents a section of the grease-extracting chamber, with detailed view of grease-collecting wheel.

Similar letters of reference designate like parts or portions in all the figures.

The letter A designates the main inclosing-chamber of the heater.

B designates a series of outer tubes, and C a series of inner tubes, forming an annular space or passage between the two, through which the feed-water moves while being heated.

D designates the upper and E the lower water-chamber of the heater, joined by the annular spaces between tubes B and C. F, the feed-water inlet, is bent to provide for the expansion and contraction of the heater-tubes.

G designates a pipe or duct providing direct communication between water-chamber E and a bottom chamber, H.

I designates a receiving-chamber for exhaust-steam, from which the steam passes up through the tubes C.

J designates a grease-collecting wheel, which is caused to revolve by the movement of the steam as it enters the receiving-chamber.

The wheel J is fitted with a hub, K, revolving upon the connecting-pipe G.

M is the exhaust-inlet, preferably set at a tangent to the circle of the receiving-chamber to guide the entering steam directly against the face of the wheel-blades. 55

N is the exhaust-outlet.

O is the feed-water outlet leading to the boiler.

The chamber I is preferably formed with a conical bottom to provide drainage for the grease as it collects. The circular portion m forms a gutter, from which it is blown out through blow-pipe n.

n' and n² are blow-off nozzles for cleansing chambers A and E of any settlement. 65

In the operation of the heater, steam enters the receiving-chamber I, and, impinging against the blades of wheel J, causes it to revolve, and while in contact with the blades it leaves the grease adhering to the metal. By 70

the revolution of the wheel J greater and more effective contact is brought about between the wheel-faces and the steam, resulting in a thorough cleansing of the steam of all grease before it enters the tubes C; also, 75

the grease is caused by centrifugal force to move toward the periphery of the wheel J, whence it is thrown against the vertical walls of the chamber or drops to the gutter m and is blown out through pipe n. In the heater, 80

as shown, the steam passes from the chamber I to and through the tubes C to the upper portion of the main chamber A, thence down about the larger tubes, B, to the outlet-nozzle N. The water of condensation is blown out 85

through pipe n². The feed-water to be heated enters the chamber D through pipe F, and passes down through the annular spaces between pipes B and C to lower chamber, E, whence it passes through pipe G to the bottom 90 chamber, H, where, the water being quiet, the materials of heavier gravity settle to the bottom and are blown out at n³.

Any style of heater may be used in connection with the two cleansing-chambers, it being only necessary that the steam for heating shall enter chamber I and the feed-water shall be discharged through settling-chamber H. Where the water is clean, chamber H may be omitted and the feed discharged from 100 chamber E direct, pipe G taking the place of boiler-connection O.

What we claim as new, and desire to secure by Letters Patent, is—

1. In combination with the heating-chamber of a feed-water heater, an exhaust-steam-receiving chamber, a revolving grease-collector located within said receiving-chamber, and a discharge-pipe, *n*, substantially as set forth.
2. In a feed-water heater, in combination with the heating-chamber, a steam-receiving chamber, *I*, revolving grease-collector *J*, located within said chamber *I*, connecting-pipe *G*, and chamber *H*, substantially as and for purposes set forth.
3. In a feed-water heater, in combination with the main inclosing-chamber *A*, tubes *C*

and *B*, connected chambers *D* and *E*, pipe *G*, exhaust-receiving chamber *I*, grease-collector *J*, and settling-chamber *H*, substantially as and for purposes specified. 20

4. In a feed-water heater, the combination of the tubes *B* and *C*, chambers *D* and *E*, connected by said tubes *B* and *C*, exhaust-receiving chamber *I*, grease-collector *J*, and discharge-tube *G*, substantially as and for purposes set forth. 25

HENRY VOGT.
ROBERT H. BURNS.
